G. A. Lilliendahl

UNITED STATES PATENT OFFICE.

G. A. LILLIENDAHL, OF NEW YORK, N. Y.

BURGLAR-ALARM.

Specification of Letters Patent No. 22,959, dated February 15, 1859.

To all whom it may concern:

Be it known that I, G. A. LILLIENDAHL, of the city, county, and State of New York, have invented a new and Improved Burglar-
5 Alarm; and I do hereby declare that the following is a full, clear, and exact description of the same, reference being had to the accompanying drawings, making part of this specification, in which—

10 Figure 1 represents a longitudinal vertical section of my invention, as applied to a door. Fig. 2, is a side elevation of do., as applied to a window, and, Fig. 3, is a plan or top view of the same.

15 Similar letters of reference in the three figures indicate corresponding parts.

This invention consists in arranging a slide the outer end of which is bent up so as to form a lip and the edges of which are 20 turned over so as to fit over a plate which is provided with spurs to secure the same in the required spot and which is also provided with a lip similar to the one formed by the end of the slide, so that a cartridge 25 filled with some highly explosive substance when placed on the slide between the two aforesaid lips is exploded by the slightest pressure on the slide or on the plate.

To enable others skilled in the art to fully 30 understand and construct my invention I will proceed to describe it.

A, is a plate the edges of which are bent over wires B, which are turned down and provided with sharp points so as to form 35 spurs a, a, and one end of the plate A, is turned up so as to form a lip b. The edges which are bent over the wires B, form the guides for a slide C, the edges of which are bent over so as to fit nicely over the plate 40 A, and the outer end of this slide is turned up so as to form a lip c. This lip must be made somewhat higher and stronger than the first lip b, so that when the device is used for a door which does not come down

45 close to the floor, the lip c, is reached by the door and that the same, when the door strikes against it, don't bend down. Between the two lips b, and c, and on the slide C, a cartridge D, is placed, which is so 50 constructed that it explodes by pushing its ends together. Two strips of paste board d, d, are cut out to fit the slide C, and rough surfaces e are attached to them, at a certain distance from their ends, and the end of one 55 strip is placed on the rough surface of the

other. The space so formed between the two surfaces e, e, is charged with fulminating mercury or some other substance of highly explosive character, and which when exploded gives a loud report, and the whole 60 is covered over with thin paper which offers but little resistance against pushing the ends of the cartridge D together.

The operation is as follows:—After the device has been set in working order by 65 placing the cartridge on the slide C, and between the lips b and c, it is placed before a door at a little distance from the same as represented in Fig. 1, so that when the door is opened it strikes against the lip c, and 70 pushes the slide C, over the plate A. The latter one is prevented from giving way by the spurs a, a, which catch in the carpet if such a one be on the floor, or which are driven into the floor sufficiently to offer the 75 necessary resistance. By thus pushing the slide over the plate the lips c and b are brought closer together and the cartridge explodes so that the report of the same calls the attention of other persons in the house 80 to the spot.

This device may be applied with equal advantage to a window as represented in Fig. 2. In this case the plate A, is fastened to the frame of the upper sash by 85 driving the spurs a, in the same as represented in the drawing and at such a distance from the lower sash that the slide C, with its lip c, rests on the upper edge of the lower sash leaving room enough between 90 the lips b, and c, for the cartridge. In this case the cartridge is exploded by raising the lower sash or by pushing down the upper one, so that my device serves as a perfect 95 safeguard against all persons which intend to burglariously enter a house or room.

Having thus described my invention what I claim as new and desire to secure by Letters Patent, is,

The arrangement of the slide C, and 100 plate A, with the lips c, and b, so that a cartridge placed on the slide and between the two lips is exploded by pushing the slide in substantially as and for the purpose specified.

G. A. LILLIENDAHL.
